By Thos. Wright, Atty's.

UNITED STATES PATENT OFFICE.

ANTON OHNEMUS, OF QUINCY, ILLINOIS, ASSIGNOR TO THE EXCELSIOR
STOVE AND MANUFACTURING COMPANY, OF SAME PLACE.

DESIGN FOR A STOVE.

SPECIFICATION forming part of Design No. 31,872, dated November 21, 1899.

Application filed October 26, 1899. Serial No. 734,887. Term of patent 7 years.

To all whom it may concern:

Be it known that I, ANTON OHNEMUS, a citizen of the United States, residing at Quincy, in the County of Adams and State of Illinois, have invented and produced a new and original Design for a Stove, of which the following is a specification, reference being had to the accompanying drawing, forming part thereof.

The drawing is a perspective view showing my design.

As shown in the drawing, the leading or material feature of my design consists of a body A, having a bulged front B and a rearward extension C. Surmounting the body, its front, and its rear extension is a top D, having circles E. Extending upwardly from the top is a panel F, near the top of which is a hori-

zontal ledge G. On each side of the panel is a flat projection H. Extending forwardly from the body A is a projection I, having a flat overhanging top J, and beneath the body is a base K, depending from which are legs L. The base, the legs, the body, the projections and front of the body, the panel, and the ledge of the panel are all decorated with scroll-like figures, as shown in the drawing.

I claim as my invention—

The design for a stove herein shown and described.

ANTON OHNEMUS.

In presence of—

JOHN J. FISHER,
THEO. EHRHART.
